US0D1048730S

(12) **United States Design Patent** (10) **Patent No.:** **US D1,048,730 S**
(45) **Date of Patent:** **** Oct. 29, 2024**

(54) **DIGITAL PHOTO FRAME**

(71) Applicant: **SHENZHEN ZHENYUEXING MOLDING CO., LTD**, Shenzhen (CN)

(72) Inventor: **Donglin Jiang**, Huaihua (CN)

(73) Assignee: **SHENZHEN ZHENYUEXING MOLDING CO., LTD**, Suzhou (CN)

(**) Term: **15 Years**

(21) Appl. No.: **29/904,833**

(22) Filed: **Oct. 12, 2023**

(30) **Foreign Application Priority Data**

Sep. 26, 2023 (EM) 015035287-0001

(51) **LOC (14) Cl.** **06-07**

(52) **U.S. Cl.**

USPC **D6/308; D6/310**

(58) **Field of Classification Search**

USPC D6/300, 301, 308, 314, 553, 310, 311, D6/312, 313

CPC G09G 2380/16; A47G 1/0616

(57) **CLAIM**

The ornamental design for a digital photo frame, as shown and described.

DESCRIPTION

FIG. 1 is a front, right and top perspective view of a digital photo frame, showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of portion 9 of FIG. 1 thereof; and,

FIG. 10 is an enlarged view of portion 10 of FIG. 2 thereof. The broken lines shown in the drawings illustrate portions of the digital photo frame that form no part of the claimed design.

The dot-dash broken lines depict the boundaries of the enlargements that form no part of the claimed design.

1 Claim, 10 Drawing Sheets
